1 Claim

ABSTRACT OF THE DISCLOSURE

An extrusion matrix with external conicity clamped with strong pre-stressing in a conical pressure cylinder, the matrix being releasable under influence of an expelling force acting on the forging.

BACKGROUND OF THE INVENTION

Field of the invention

The present invention relates to a means for performing extrusions in a cold forging press, said means comprising a pressure chamber and a matrix with external conicity arranged at the bottom of said pressure chamber, the pressure chamber being radially limited by an annular body intended to enclose said matrix with strong pre-stressing and shaped with an internal conicity corresponding to the external conicity of the matrix, said means comprising an expelling mechanism intended to exert an expelling force on the finished forging.

The prior art

When cold forging in a forging press, it is extremely important to prevent the forging from sticking to adjacent surfaces of the tool, and for this reason the substance is supplied with a lubricating layer by means of a relatively complicated surface treatment. During extrusion the lubricating layer is subjected to considerable wear which can easily mean that the lubrication is insufficient during expulsion and the work piece is damaged.

SUMMARY OF THE INVENTION

The above-mentioned disadvantage is avoided with a device according to the invention which is based on the principle of eliminating the pressure of the matrix against the object during expulsion.

A device according to the invention is characterised in that said conicity is achieved narrowing in the pressing direction and that the matrix within a certain range is movable under the influence of the expelling force transmitted from the forging to the matrix.

With a device according to the invention the special difficulties are also eliminated which arise when the object produced during extrusion is so long that there is a danger of its snapping or being deformed during expulsion.

2

BRIEF DESCRIPTION OF THE DRAWING

The invention will be described in the following with reference to the accompanying drawing where FIG. 1 and FIG. 2 show the device in longitudinal section, FIG. 1 showing the device in the final stage of forging and FIG. 2 during expulsion of the forging.

DESCRIPTION OF THE PREFERRED EMBODIMENTS

10 The matrix 1 is externally conical and fits into an annular body 2 which is pre-stressed in the pressure cylinder 3 of the tool. During forging the matrix will be pressed down until it stops against a ring 4 above the pressure-equalising plate 5 and is thus, due with the external cone, compressed to suitable radial pre-stressing. This is chosen so that when the matrix during expulsion moves upwards out of the cone, the radial expansion of the matrix will be sufficiently great for its grip on the extruded detail to cease. Thus in this way the pressure of the matrix on the final object is eliminated as desired. The matrix 1 is prevented from rising too high during expulsion since a stop on this matrix stops against the ring 4 which is manufactured in parts to enable it to be mounted. The system may also be designed so that the lining 6 of the moulding space is also provided with sloping surfaces so that the pre-stressing of the lining ceases when it is moved upwardly. In this way even the unextruded part of the forging 7 can be pushed out under such conditions that no pressure, or only moderate pressure, is exerted against the wall of the moulding space.

I claim:

1. Means for performing extrusions in a cold forging press, said means comprising means forming a pressure chamber, and a matrix with external conicity arranged at the bottom of said pressure chamber, the pressure chamber forming means including an annular body into which said matrix can enter, said annular body having strong pre-stressing and being shaped with an internal conicity corresponding to the external conicity of the matrix, said matrix decreasing in cross-section in the pressing direction, and said pressure chamber forming means and said matrix having cooperating projection and recess means for allowing limited movement of the matrix within a certain range 35 with respect to the pressure chamber forming means under the influence of an expelling force transmitted from a forging to the matrix.
